UNITED STATES PATENT OFFICE.

WILLIAM J. HUDSON, OF MUSCATINE, IOWA, ASSIGNOR TO WESTINGHOUSE ELECTRIC & MANUFACTURING COMPANY, A CORPORATION OF PENNSYLVANIA.

ALTERNATING-CURRENT MOTOR-CONTROL SYSTEM AND CONTROL SWITCH THEREFOR.

Application filed January 25, 1919. Serial No. 273,074.

To all whom it may concern:

Be it known that I, WILLIAM J. HUDSON, a citizen of the United States, and a resident of Muscatine, in the county of Muscatine and State of Iowa, have invented a new and useful Improvement in Alternating-Current Motor-Control Systems and Control Switches Therefor, of which the following is a specification.

10 My invention relates to alternating-current magnets and switches and has particular relation to the control of motors thereby.

One object of my invention is to provide 15 an improved alternating-current magnet.

A second object of my invention is to provide such a magnet which shall be especially adapted for short-circuiting the resistor in the secondary-winding circuit of 20 a wound-rotor induction motor.

Other objects will appear hereinafter and will be embodied in the appended claims.

According to the form of my invention herein chosen for purposes of illustration, 25 I provide a magnet core having three legs, upon the central leg of which is pivotally mounted an armature member having pole pieces for co-operating with the two end legs. Coils, which are respectively mainly reactive and resistive, are connected across 30 the slip rings of the secondary winding of the motor, and are respectively wound upon the end legs. The armature member carries a switch member for short-circuiting portions 35 of the resistor which is in circuit with the secondary winding. The characteristics of the two coils are such that at a lower speed than that for which the switch is set, the armature will be held in engagement with one of the end legs to maintain the switch open. As the motor speed increases, 40 the switch will be closed by the armature member being actuated into engagement with the other end leg.

45 My invention will be described in connection with the accompanying drawing, in which the single figure is a diagrammatic view of circuits and apparatus embodying my invention, the resistor which is in circuit with the wound secondary winding being shown as adapted to be short-circuited in two steps by means of two switches embodying different forms of my invention.

50 Line conductors 1, 2 and 3, which may be connected to any suitable source of three-

phase alternating current, supply energy to an induction motor 4 having a phase-wound secondary member. The secondary winding of the motor is connected through the usual slip rings to external resistors 5, 6 and 7. The resistors are controlled by switches 8 and 9, the switch 8 having a movable member 10 which is adapted to close to engage stationary members 11, 12 and 13, respectively connected to intermediate points of the resistors 5, 6 and 7 and the switch 9 having a movable member 14 adapted to close to engage stationary switch members 15, 16 and 17, respectively connected to points between the secondary 70 phase windings and the resistors 5, 6 and 7. The switch 8 will thus short-circuit, when closed, a portion of each of the resistors 5, 6 and 7 and the switch 9 the remaining portion. 75

The switches 8 and 9 each comprise a core member 18 having end legs 19 and 20 and a central leg 21. Upon the central leg is pivotally mounted an armature member 22 having pole pieces 23 and 24 for co-operating with the end legs 19 and 20, respectively. The armature member 22 carries the movable switch member 10 or 14 which is adapted to be closed when the pole piece 23 has been actuated into engagement 80 with the leg 19. The armature 22 is shown in the normal, inoperative position with the pole piece 24 engaging an adjustable, non-magnetizable stop member 25 which is adapted to limit the movement of the armature 22 with respect to the leg 20, thereby providing for different sized air gaps between the pole piece 24 and the leg 20. The armature 22 is provided with a weight member 26 for actuating the armature 22 85 into the inoperative, illustrated position. 90

The legs 19 and 20 are respectively provided with coils 27 and 28, the former of which is mainly reactive and the latter mainly resistive. For purposes of illustration, I have shown a resistor 29 in series with the coil 28 but it will be understood that the necessary resistance may be embodied in the coil itself by suitably winding properly chosen material. The coils 27 and 105 28 are connected in parallel across conductors 30 and 31, which are respectively connected across two of the slip rings of the secondary winding.

The operation is as follows. When the 110

motor has been started, by connecting the primary windings to the line through the closing of a switch, not shown, current will be induced in the secondary windings and will flow through the resistors 5, 6 and 7. The motor will then begin to speed up. It will be obvious that by reason of its connections, and its nature, the coil 27 will be responsive to both voltage and frequency, so that it will exert a force upon the armature 22 which is approximately constant for all speeds of the motor. The other coil 28, being responsive to voltage principally, the force exerted by it upon the armature 22 will depend upon the speed of the motor. As the motor speed increases, the frequency and the voltage impressed on the two coils decrease in proportion to the per cent slip. The flux produced by the coil 28 will ultimately decrease to a value less than that created by approximately constant force of the coil 27, whereupon the pole piece 23 of the armature 22 will be actuated into engagement with the leg 19, closing the switch members 10, 11, 12 and 13 (assuming that the switch 8 has been adjusted to close before the switch 9) and resulting in short-circuiting a portion of the resistors 5, 6 and 7. The motor speed then further increases and ultimately the coil 27 will overpower the coil 28 of the switch 9, causing the closure of the switch members 14, 15, 16 and 17. The resistors 5, 6 and 7 are now entirely short-circuited and the motor is running at normal speed. A holding coil 27^a, controlled by line voltage, is employed to maintain switch 9 closed. Any other well known holding means may be employed.

In the above-description of the operation, it has been assumed that the switch 8 will close before the switch 9. This is not because of the particular structure illustrated, but as a result of proper design of the coils, the adjustment of the stop 25 and the size of the weight member 26. Obviously, any number of these switches may be employed, any or all of which may be of the type indi-

cated at 8 or 9. It will be understood that these switches may be employed not only in connection with motors operating in one direction only, but with reversing motors as well and whether the secondary resistor is balanced or unbalanced.

Obvious changes will occur to those skilled in the art and I therefore desire that the appended claims be construed broadly except in so far as limitations may be specifically imposed therein.

I claim as my invention:

1. The combination with an alternating-current motor, of a resistor connected thereto, a switch for short-circuiting said resistor, means including shunt circuits from said motor for controlling said switch in accordance with the relation between the reactance and the resistance of said circuits.

2. The combination with an alternating-current motor having primary and secondary windings and a resistor in circuit with said secondary winding, of a switch for short-circuiting said resistor having reactive and resistive opposing actuating coils connected across two leads of said secondary winding.

3. The combination with a dynamo-electric machine, of a translating device connected thereto, means adapted to render said device ineffective, and means including shunt circuits from said machine for controlling the first-named means in accordance with the relation between the reactance and the resistance of said circuits.

4. The combination with a dynamo-electric machine having co-operating stationary and movable windings and a resistor in circuit with one of said windings, of a switch for rendering said resistor ineffective and having reactive and resistive actuating coils connected across a portion of said resistor.

In testimony whereof, I have hereunto subscribed my name this 11th day of January, 1919.

WILLIAM J. HUDSON.
